UNITED STATES PATENT OFFICE.

CARLOS TOURIGNE, OF SAN FRANCISCO, CALIFORNIA.

PATTERN-MAKING MACHINE.

SPECIFICATION forming part of Letters Patent No. 317,687, dated May 12, 1885.

Application filed January 16, 1885. (No model.)

To all whom it may concern:

Be it known that I, CARLOS TOURIGNE, of the city and county of San Francisco, and State of California, have invented an Improvement in Pattern-Making Machines; and I hereby declare the following to be a full, clear, and exact description thereof.

My invention relates to a new and useful machine for laying or cutting out patterns, either directly from the object to be fitted, whether of a curvilinear or plane surface, or from another pattern.

My invention, while applicable to the making of all patterns, is particularly intended for laying or cutting out the patterns for uppers of shoes, whereby they may be conformable to the last in every particular, either measurement for measurement or proportionally. With this in view, I have illustrated my machine in connection with a last, especially as it will show the principal feature of my invention, namely, the ability to transfer the outline and measurements of a curvilinear surface to a plane surface.

My invention consists in the employment of a string, cord, or other flexible line, so mounted and guided and centered as that one end may be made to follow the outline of the body while lying upon and moving over in perfect parallelism with its curvilinear surface, and its other end may receive motion from the first end to register or indicate its movements, thus delineating them both in outline and measurement and forming the pattern.

My invention consists, further, in a suitable frame, an adjustable last-holder, a movable and adjustable string-holder on one side, and a movable and adjustable pencil or knife holder on the other, a mechanism for transmitting the movements of the string to the pencil or knife, a means for proportionally altering the movement of the pencil or knife, a swinging table for the work, and various details of construction, all of which I shall hereinafter fully explain by reference to the accompanying drawings, in which—

Figure 1 is an elevation of my machine. Fig. 2 is a plan of same.

A is a pedestal, here shown of a T shape. Around the lower portion of its stem is fitted an eye or sleeve, b, of an arm B. This sleeve is a split one, and is fixed to its position by

impinging lugs b', which are tightened by a bolt and nut, b², whereby the sleeve may be tightened upon the stem of the pedestal, or may be slackened for the purpose of allowing the arm B to have an oscillatory movement thereon.

In the end of the arm B is fitted a holder, C, here shown of a U shape, and having a downwardly-extending stem, c, which passes through a socket in the end of the arm B, and is set by a screw, c', whereby said holder may be adjusted in position vertically, and may also have a rotary movement upon its stem c.

In the ends of the holder C are fitted screws D, which act as centers or holders for the last X. The depending arms a of the pedestal are made tubular, and through the left-hand arm extends a hollow shaft or tube, E, which, where it emerges from the hollow arm, is increased in diameter to the diameter of said arm, simply for the sake of appearance. To the lower end of the shaft E is fixed a block, F, in the lower portion of which is mounted a guide-pulley or roller, f. A square hole is made longitudinally through the block F, and receives a bar, G, one arm of which is horizontal, and the other arm, g, extends upwardly at right angles. A spring, H, here shown as a rubber strap, is secured to the block F and to the end of the bar G, and serves to keep said bar to its position in its socket.

Fitted loosely, or pivoted upon the upright arm g, is a handle, I, which is influenced by a spring, i, secured to the upright arm, and having a tendency to hold said handle up. The other arm, a, of the pedestal is also made hollow, and has extending down through it a hollow shaft, J, the lower end of which carries a block, K. This block has a longitudinal aperture through which fits a bar, L, which is held to its position by a spring-strap, l, secured to the block and to the bar.

Secured to the bar, and projecting through a suitable slot or opening in the bottom of the block K, is a spring-arm, M, in the end of which is fitted a pencil, m. A hook, m', provides for hanging the pencil up when desirable.

The lower portion of the shaft J is provided with an upwardly-extending diverging arm, j, to the top of which is pivoted a hanger, N, the lower end of which is slotted at n, and receives a pin or stud, n', from the bar L, whereby a

connection between said bar and hanger is formed.

Upon the top of the pedestal, in boxes *o*, is mounted a hollow shaft, *O*, on each end of *5* which is a beveled gear, *P*, meshing with a beveled gear, *p*, on the top of the shafts *E J*.

In the shaft *E*, near its bottom, is a guide-pulley, *q*, and on top of the arms *a* of the pedestal are guide-pulleys *Q*.

10 Near the bottom of the shaft *J* is a large guide-pulley, *R*.

S is a string or cord, made of any suitable material, and flexible in its nature. One end of the cord is attached to the bottom of the *15* handle *I*, and thence passes around pulley *f*, up through a suitable slot or hole in the block *F*, and into the hollow shaft *E*, in which it is guided upward by the pulley *q* until it emerges from the top of said shaft. It is thence guided *20* horizontally by the pulley *Q*, and enters the hollow shaft *O*, from the other end of which it emerges, and is guided downward vertically by the other pulley *Q* into the hollow shaft *J*, from the side of which it emerges near its bottom, being guided outwardly by pulley *R*, and *25* is secured directly or indirectly to the hanger *N*. The lower portion of this hanger is graduated to a scale, as shown, and has fitted upon it a traveler, *T*, which is adapted to slide up and down over the scale and to be set in any *30* suitable position by a set-screw, *t*. The end of the string passes through a hole in the base of the traveler, and is secured to a vertically-adjustable screw, *t'*, mounted in the traveler, *35* whereby the slack of the string may be taken up.

U is a table, which is shown more particularly in Fig. 2, and consists of a flat plate divided into three parts, one part or end being *40* approximately rectangular, and the other parts are two independent sectors, *u*, which are centrally pivoted at *w* on the stem of the pedestal, and are adapted to be turned back to the position shown in said figure, wherein they *45* join the rectangular portion, or to be turned forward to meet together to form a table in front.

The operation of the device is as follows: The last is set in any position that may be desired to obtain whatever center of measurement may be necessary. It has an oscillatory adjustment by reason of the pivoted arm *B* moving on the stem of the pedestal as a center, an oscillatory adjustment of the holder *C* *55* on its own stem *c*, and the vertical adjustment of said holder in its socket in the arm *B*. By these various adjustments the last may be readily turned to any position under the roller *f*, which will give whatever center of measurement may be desired, and especially by the *60* vertical adjustment can it be brought directly under the roller, by which means there will be no waste of measuring-string. When the last has been properly adjusted for one set of measurements, the handle *I* is grasped as shown, and by its downward movement the string may be brought down to lie flat upon

and over the curvilinear surface of the last; then by the movement of the hand the end of the pivoted handle, and consequently the end *70* of the string, may be made to follow the outline of the last, while that portion of the string between the handle and roller fits perfectly the contour of the curvilinear surface. The movement in pursuance of the outline is possible by reason of the ability of the bar *G* to turn with the shaft *E* as a center and the handle *I* to turn on its own center, giving thus the course of the outline, while the longitudinal movement which the bar *G* has, enables the operator to pull the handle horizontally, whereby the string is pulled upon to follow the distances of the outline, and thus its other end, acting through the hanger *N* and the longitudinally-moving bar *L*, causes the pencil to travel over a suitable piece of paper or material which is laid upon the table, thus giving not only the outline, but the proper *80* measurements, the outline movement being communicated through the various shafts and gears to the pencil which follows the same movement. The result of this is that the measurements over the curvilinear surface of the last are transmitted to the pencil, which accurately lays off equal measurements on the *85* plane surface of the paper. In this way the pattern is drawn, which has exactly such dimensions as will enable it, when cut out, to fit the curvilinear surfaces of the last.

Instead of marking with a pencil, I may substitute a knife and cut the pattern directly; or, after one pattern has been made and cut out, I can remove the last, and by turning forward the sectors *u* of the table can place said pattern thereon under the roller *f*, placing a *90* new piece of paper or material under the pencil or knife, and thus can form another pattern directly from the one first made.

It is necessary in the manufacture of shoes to make different sizes of patterns from the *100* same last. I accomplish this result by means of the traveler *T* moving over the graduated scale of the hanger *N*, for it is obvious that by moving said traveler up the nearer it approaches to the pivotal axis of the hanger the *110* greater will be the movement of the lower end of said hanger, by reason of the same movement of the string communicated from the other side, and thus the pencil will give throughout greater measurements than the *120* string on the other side indicates over the last. By moving the traveler down the reverse result is accomplished.

Having thus described my invention, what *125* I claim as new, and desire to secure by Letters Patent, is—

1. In a machine for making patterns, a string, cord, or other flexible line, one end of which is adapted and made to follow the outline of a body or object, while the other, by *130* means of proper intermediate mechanism, operates a pencil to form a corresponding outline, substantially as herein described.

2. In a machine for making patterns, a

- string, cord, or other flexible line, one portion or end of which is adapted to lie upon and in perfect parallelism with the curvilinear surface of a body or object, and to pursue its outline, 5 while the other end, by means of proper operative mechanism, operates a pencil to form a corresponding and commensurate outline on a plane surface, substantially as herein described.
- 10 3. In a machine for making patterns, a pivoted rotating block or guide, and a string, cord, or other flexible line adapted to be guided and properly centered over an object or body, in combination with a pencil operated 15 by one end of the string to move in conformity with its other end in pursuing the outline of the object or body and its intermediate operative mechanism, substantially as herein described.
- 20 4. In a machine for making patterns, a pivoted rotating block or guide and a string, cord, or other flexible line adapted to be guided and properly centered over an object or body having a curvilinear surface, in combination 25 with a pencil operated by one end of the string and by the pivoted block to move over a plane surface in conformity with its other end in pursuing the outline of the object or body, and to form a pattern having 30 equal superficies with the said body or object and the intermediate operative mechanism, substantially as described.
5. In a machine for making patterns, the pivoted rotating block F above the object or body of which the pattern is to be made, the pivoted rotating block K, and the longitudinally-moving bar L in the block K, carrying a pencil moving over a plane surface, in combination 35 with a string, cord, or other flexible line centered on the body or object by block F, and having one end adapted to follow its outline and lie upon and in complete parallelism with its surface, and having a connection between its other end and the pencil-carrying bar, whereby the distances of the first end of the string from its guided center on the object or body are indicated on the plane surface, and a connection between the oscillating blocks, whereby the movement of the string in pursuing 45 an outline is transferred to the pencil, substantially as described.
6. In a machine for making patterns, the pivoted rotating block F above the object or body of which the pattern is to be made, the pivoted rotating block K, having an arm, j' , the longitudinally-moving bar L in the block K, carrying a pencil moving over a plane surface, and the hanger N, pivoted to the top of arm j , and connected with the end of the pencil-bar L, as described, in combination with the flexible string S, centered on the body or object by block F, and its other end connected with the hanger N, and a mechanism for transmitting the oscillation of block F to block K, substantially as and for the purpose herein described.
7. In a machine for making patterns, the pivoted oscillating block F above the object or body of which the pattern is to be made, the longitudinally-moving bar G in said block, 70 and the vertically-moving pivoted handle I on the bar, the pivoted rotating block K, and the longitudinally-moving bar L in said block, carrying a pencil moving over a plane surface, in combination with the flexible string S, centered on the body or object by block F, and having one end attached to the handle I, and a connection between its other end and the pencil-carrying bar, and a mechanism by which the oscillation of block F is transmitted to block K, substantially as and for the purpose herein described.
8. In a machine for making patterns, the pivoted rotating block F above the object or body of which the pattern is to be made, the 85 longitudinally-moving spring-bar G in said block, and the vertically-moving pivoted spring-handle I on the bar, the pivoted rotating block K, having an arm, j , the longitudinally-moving spring-bar L in block K, carrying a pencil moving over a plane surface, and the hanger N, pivoted to the top of arm j , and connected with the end of the pencil-bar L, as described, in combination with the flexible string S, centered on the body or object by 90 block F, and having one end connected with handle I and the other end with the hanger N, and a mechanism by which the oscillation of block F is transmitted to block K, substantially as and for the purpose herein described. 95
9. In a machine for making patterns, the pivoted rotating block K, and longitudinally-moving spring-bar L, carrying a pencil, said block and bar being operated by means of a flexible spring pursuing the outline and measurements of a body or object, as described, in combination with a mechanism or means by which the movement of the pencil carrying bar derived from the string is altered proportionally to make a pattern of 105 proportionally-different dimensions from those of the body or object, substantially as herein described.
10. In a machine for making patterns, the pivoted rotating block K and longitudinally-moving spring-bar L, carrying a pencil, said block and bar being operated by means of a flexible string pursuing the outline and measurements of a body or object, as described, in combination with the means by which the 110 pattern formed by the pencil is changed in dimensions proportionally, consisting of the hanger N, pivoted to the block K, and connected with the pencil-bar L and the traveler T on said hanger, to which the string is attached, substantially as herein described. 115
11. In a machine for making patterns, the pivoted rotating block K and longitudinally-moving spring-bar L, carrying a pencil, said block and bar being operated by means of a flexible string pursuing the outline and measurements of a body or object, as described, in combination with the means by which the pattern formed by the pencil is changed in dimensions proportionally, consisting of the hanger N, pivoted to the block K, and connected with the pencil-bar L and the traveler T on said hanger, to which the string is attached, substantially as herein described. 120
12. In a machine for making patterns, the pivoted rotating block K and longitudinally-moving spring-bar L, carrying a pencil, said block and bar being operated by means of a flexible string pursuing the outline and measurements of a body or object, as described, in combination with the means by which the pattern formed by the pencil is changed in dimensions proportionally, consisting of the hanger N, pivoted to the block K, and connected with the pencil-bar L and the traveler T on said hanger, to which the string is attached, substantially as herein described. 125
13. In a machine for making patterns, the pivoted rotating block K and longitudinally-moving spring-bar L, carrying a pencil, said block and bar being operated by means of a flexible string pursuing the outline and measurements of a body or object, as described, in combination with the means by which the pattern formed by the pencil is changed in dimensions proportionally, consisting of the hanger N, pivoted to the block K, and connected with the pencil-bar L and the traveler T on said hanger, to which the string is attached, substantially as herein described. 130

mensions proportionally, and the slack of the string taken up, consisting of the hanger *N*, pivoted to the block *K*, and connected with the pencil-bar *L*, the traveler *T* on said hanger, 5 and the screw *t* on the traveler to which the string is attached, substantially as and for the purpose herein described.

12. In a machine for making patterns, the pivoted rotating block *F*, longitudinally-moving spring-bar *G*, and the vertically-adjustable pivoted spring-handle *I*, arranged as described, the rotating block *K*, having arm *j*, the longitudinally-moving spring-bar *L*, having spring-arm *M*, with pencil *m*, the hanger *N*, pivoted to arm *j*, and connected with bar *L*, and the vertically-moving traveler *T* on the hanger, in combination with the flexible string *S*, one end of which is secured to handle *I*, and is guided by the block *F*, and the other is attached to the traveler *T*, and a mechanism by which the movement of block *F* is transmitted to block *K*, substantially as and for the purpose herein described.

13. In a machine for making patterns, the pedestal *A*, having arms *a*, the pivoted block *F* at the extremity of one arm, the longitudinally-moving angled bar *G* in said block, and the vertically-moving pivoted handle *I* on the bar, the pivoted block *K* in the extremity of 30 the other arm, and the longitudinally-moving bar *L* in said block, and the pencil *m*, carried by the bar, in combination with the flexible string *S*, attached by one end to handle *I*, and guided by block *F*, and operating by its other end the pencil-bar *L*, whereby the measurements of the string are transferred to the pencil, and a mechanism by which the oscillatory movement of the block *F* is transmitted to the block *K*, whereby the outline pursued 40 by one end of the string is transferred to the pencil, substantially as herein described.

14. In a machine for making patterns, the pedestal *A*, having hollow arms *a*, the hollow shafts *E J* within said arms, having top gears, *p*, and the horizontal hollow shaft *O*, having end gears, *P*, meshing with gears *p*, in combination with the blocks *F K* on the extremities of the shafts *E J*, the longitudinally-moving angled spring-bar *G* in block *F*, having the vertically-adjustable pivoted spring-handle *I*, the longitudinally-moving bar *L* in block *K*, having pencil *m*, and the flexible string *S*, attached by one end to handle *I*, and thence guided by block *F*, and passing through shafts *E*, *O*, and *J*, and adapted to operate by its other end the bar *L*, substantially as herein described.

15. In a machine for making patterns, the pedestal *A*, having hollow arms *a*, the hollow shaft *E* in one arm, block *F* on the extremity of the shaft, longitudinally-moving angled spring-bar *G* in the block, and the vertically-adjustable pivoted spring-handle *I* on the bar, arranged as described, the hollow shaft *J* in the other arm, having block *K* on its extremity, with arm *j*, the longitudinally-moving spring-bar *L*, carrying pencil *m*, and the hanger

N, pivoted to the arm *j*, and connected with the bar *L*, in combination with the means by which the movement of block *F* is transmitted to block *K*, consisting of the horizontal hollow shaft *O*, and the gears *P p*, on the shafts *O E J*, and the flexible string *S*, secured at one end to the handle *I*, and guided by block *F*, and at the other end to hanger *N*, said string passing through the hollow shafts, substantially as herein described. 75

16. In a machine for making patterns, the pedestal *A*, having hollow arms *a*, the hollow shaft *E* in one arm, block *F* on the extremity 80 of the shaft, longitudinally-moving angled spring-bar *G* in the block, and the vertically-adjustable pivoted spring-handle *I* on the bar, as described, the hollow shaft *J* in the other arm, having block *K*, with arm *j*, the longitudinally-moving spring-bar *L*, carrying pencil *m*, and the hanger *N*, pivoted to the arm *j* and connected with the bar *L*, in combination with the hollow shaft *O*, having gears *P*, and the gears *p* on the tops of the shafts *E J*, whereby 90 the movement of block *F* is transmitted to block *K*, the guide-pulley *f* in block *F*, the pulleys *Q* on the arms *a*, and pulley *R* in the shaft *J*, and the flexible string *S*, connected with handle *I* and hanger *N* and passing 95 through the shafts over the pulleys, substantially as herein described.

17. In a machine for making patterns, the adjustable object-holder *C*, in combination with the pivoted block *F* over the object, the 100 flexible string *S*, guided and centered by the block, and adapted to follow the outline of the body and the contour of its surface, as described, and a pencil-carrying mechanism operated by the pivoted block *F* and string 105 *S*, whereby the outline and dimensions of the body are made on a plane surface, substantially as herein described.

18. In a machine for making patterns, the swinging arm *B* and vertically-adjustable 110 pivoted holder *C* therein, adapted to receive and adjust the body the pattern of which is to be taken, in combination with the pivoted block *F* over the body, the flexible string *S*, guided and centered by the block, and adapted 115 to follow the outline of the body and the contour of its surface, as described, and a pencil-carrying mechanism operated by the pivoted block *F* and string *S*, whereby the outline and dimensions of the body are made on 120 a plane surface, substantially as herein described.

19. In a machine for making patterns, the pedestal *A*, carrying the adjustable object-holder *C*, the pivoted and adjustable string-guiding mechanism over the object, and the pivoted and adjustable pencil mechanism at the other side of the machine, and the flexible string *S*, all operating as described, in combination with the three-part table *U*, 125 consisting of an end portion over which the pencil moves, and two sector portions, *u*, pivoted to the stem of the pedestal, substantially 130 as and for the purpose herein described.

20. A machine for making patterns, consisting of the combination of the pedestal A, having hollow arms *a*, the adjustable object-holder C, the hollow shafts E J in the arms *a*,
5 the blocks F K on the shafts, the longitudinally-moving spring-bars G L in the blocks, the vertically-adjustable pivoted spring-handle I on bar G, and the spring-arm M on bar L, carrying pencil *m*, the pivoted hanger N,
10 joining bar L, the hollow shaft O, gearing with shafts E J, the table U, over which the pencil moves, and the flexible string S, connected

with the handle I and hanger N and passing through the block F, and shafts E O J over suitable pulleys, all arranged and adapted to 15 operate substantially as and for the purpose herein described.

In witness whereof I have hereunto set my hand.

CARLOS TOURIGNE.
